UNITED STATES PATENT OFFICE.

OTTO ZWIETUSCH, OF MILWAUKEE, WISCONSIN.

FOUNTAIN FOR CARBONATED LIQUIDS.

SPECIFICATION forming part of Letters Patent No. 506,355, dated October 10, 1893.

Application filed September 22, 1892. Serial No. 446,533. (No model.)

To all whom it may concern:

Be it known that I, OTTO ZWIETUSCH, a citizen of the United States, residing at Milwaukee, in the county of Milwaukee and State of Wisconsin, have invented a new and useful Improvement in Fountains for Carbonated Liquids, of which the following is a specification.

My invention relates to improvements in fountains for containing carbonated liquids; and my several improvements will be pointed out in the course of the following description, reference being had to the accompanying drawings, in which—

15 Figure 1 is a view of my improved fountain in vertical section, with the siphon detached; Fig. 2, a sectional view of the siphon and attachments; Fig. 3, a plan view of a detail, and Fig. 4 a partly sectional view of a detail.

20 The objects of my invention are to facilitate the manufacture of the fountain; also to give it exceptional strength; and also to adapt it to be conveniently rolled about upon its lower edge without injury to the floor.

25 A is the exterior shell, formed in one piece of steel. B is a tin lining, fitting snugly within the shell A, and terminating at a considerable distance above the lower end of the latter, as shown. The lining B having been

30 introduced into the shell A, the bushing C is next inserted through the opening in the top. The shell A and lining B are notched at the top, preferably on two opposite sides of the opening for the bushing, as shown at t, (though one notch only, or more than two

35 may be employed,) and lugs, s, on the bushing, somewhat smaller than the notches enter the latter. The effect of this is two-fold:—First, the lugs in the notches prevent turning 40 of the bushing, with consequent torsion of the lining B, when the collar D is screwed into place against the annular bearing-plate a, which is fixed to the shell, and, secondly, the notches, being somewhat larger than the

45 lugs, serve as outlets for any air that may be confined between the shell A and lining B. The lining B and bushing C having been introduced, the next step in the manufacture is to secure the bottom in place. This is done

50 as follows: A dish-shaped disk E of tin, similar to that constituting the lining B, is soldered to the base of the latter, and consti-

tutes the bottom lining. Next, a wedge-shaped ring, F, of solder or other suitable material is placed against the under side of the bottom lining, as shown, and a dish-shaped steel plate, G, conforming to the bottom lining, E, and interposed ring F, and provided with an annular flange, r, of such height as to reach to the lower end of the outer shell A, is set within the shell. An annular plate, H, fitting within the flange r, and flanged at its top, as shown at q to lie against the steel plate G is then introduced, and its lower portion p turned outward around the lower ends of the steel shell A and flange r of the steel bottom-plate G, and also, preferably, around a wire ring, o, fitting against the lower outer edge of the steel shell A, thereby forming a broad, rounded tire or tread on which the fountain may be rolled without injuring the floor. The shell A, flange r, and annular plate H are all secured together by rivets n.

The parts having been put together as above described, the lower portion of the fountain is immersed in a bath of molten solder to a height somewhat above the rivets, the effect of which is to seal all the crevices. The purpose of the wedge-shaped ring F is to fill out the space between the shell, the lining and the bottom, so that when pressure is brought against the block-tin lining the latter will neither stretch nor burst.

I is the siphon-pipe, which is of the usual construction, except that the handle m of the valve, l, is made to perform a double function. That is to say, it has a slight vertical play upon the valve stem, upon which, unless restrained, it turns as a swivel. The handle has a sleeve, k, provided with a notch, i, and the valve stem is provided with a pin, h, and with an enlargement g at its upper end. When the handle is to be used to operate the valve the notch i is brought down over the pin; but when the fountain is being rolled on the floor upon its lower edge, the handle m is raised, so that while it is held firmly in the hand the valve-stem may revolve freely within it, the pin being out of engagement with the recess. This construction greatly facilitates handling of the fountains.

What I claim as new, and desire to secure by Letters Patent, is—

1. In a fountain for carbonated liquids, the

combination with the metal shell A, and tin lining B, fitting closely within the shell A, and terminating above the lower end thereof, of means for sealing the bottom of the fountain, comprising the tin disk E, soldered to the lower end of the lining B, ring F of solder, or other suitable material placed against the lower margin of the disk E, and metal disk G, conforming to the disk E and ring F, and having the flange r fitting against the interior of the shell A and riveted thereto, substantially as described.

2. In a fountain for carbonated liquids, the combination with the shell A, lining B, inner disk E, ring F of solder, or other suitable material and outer disk G having the flange r, of the annular flanged plate H, secured to the flange r and shell A by rivets, and having its lower end bent around the lower ends of said flange and shell, substantially as described.

3. In a fountain for carbonated liquids, the combination with the shell A, lining B, inner disk E, ring F of solder, or other suitable material and outer disk G having the flange r, of the wire ring o fitting against the outer lower edge of the shell A, and the annular

plate H, riveted to the flange r and shell A, and having its lower end bent over the lower ends of said flange and shell and around the wire ring o, substantially as described. 30

4. In combination with the siphon pipe and valve of a fountain for carbonated liquids, the valve-stem l thereof provided with a revoluble handle m, and means for securing the handle at will against rotation, whereby the handle may be used interchangeably as the agent for operating the valve and as a swivel to aid rolling the fountain upon its lower edge, substantially as described.

5. In combination with the siphon pipe and valve of a fountain for carbonated liquids, the valve-stem l thereof having the pin h and enlargement g at its top, and handle m upon the sleeve k, revoluble and longitudinally movable upon the stem l, and provided with 45 the notch i to engage the pin h, substantially as described and for the purpose set forth.

OTTO ZWIETUSCH.
